FISHING LURE RETRIEVER

Samuel D. Wantland, 6329 Hurstgreen Lane,
St. Louis, Mo. 63123

Filed May 12, 1972, Ser. No. 252,967

Term of patent 14 years

Int. Cl. D22—05

U.S. Cl. D22—31

The ornamental design for a fishing lure retriever, as this invention;

FIG. 2 is a front elevation view of FIG. 1;

FIG. 3 is a top plan view of FIG. 1; and

FIG. 4 is a right end elevation view of FIG. 2, the end opposite being a mirror image thereof.

I claim:

The ornamental design for a fishing lure retriever, as shown and described.
